UNITED STATES PATENT OFFICE.

CLINTON M. STONE, OF FAYETTE COUNTY, INDIANA, ASSIGNOR TO HIMSELF,
AND LEWIS P. ZELLER, OF CONNERSVILLE, INDIANA.

AUTOMATIC GATE.

SPECIFICATION forming part of Letters Patent No. 672,924, dated April 30, 1901.

Application filed January 18, 1901. Serial No. 43,703. (No model.)

To all whom it may concern:

Be it known that I, CLINTON M. STONE, a citizen of the United States, residing in Fayette county, Indiana, (post-office address Conn-
5 nersville, Fayette county, Indiana,) have invented certain new and useful Improvements in Automatic Gates, of which the following is a specification.

This invention pertains to automatic gates
10 of the load-opening type involving a hinged gate whose pivot-axis is thrown out of the vertical by the pulling of cables through the medium of trip-levers acted upon by the passing vehicle, the approaching vehicle causing
15 the gate to swing open and the departing vehicle causing it to swing shut. Like many gates of this class, my improved gate disturbs the verticality of the hinge-axis of the gate by moving the lower pintle in the arc of a
20 circle.

My improvements relate to certain details of construction whereby there is secured a superior degree of certainty in operation and a greater degree of permanency of operative
25 conditions.

My improvements will be readily understood from the following description, taken in connection with the accompanying drawings, in which—

30 Figure 1 is a perspective view of a gate embodying my improvement; Fig. 2, a plan, part horizontal section and somewhat diagrammatic, of the parts at the shifting hinge-pintle; Fig. 3, a perspective view of the parts
35 at the shifting pintle, and Fig. 4 a side elevation of one of the tripping devices.

In the drawings, 1 indicates the hinge-post of the gate; 2, the latch-post, the same appearing in Fig. 1 as being cut off low enough
40 down to expose the catch 6; 3, the holding-post, designed to hold the gate latched in open position; 4, the gate, hinged to post 1 and latching to post 2 when closed and to post 3 when open; 5, a latch-spring upon the gate, adapted to spring into engagement with catches upon posts 2 and 3 and to be disengaged from those catches when the free end of the gate is sufficiently elevated, this spring being an inwardly-yielding blade secured at
45 its upper end to the latch-stile of the gate, the lower end of the spring being free; 6, a

fixed catch upon post 2, behind which the lower end of spring 4 engages, the ends of the catch being beveled, so that as the gate closes it will force the lower end of the spring 55 inward and permit it to engage behind the catch when the gate is in closed position, the catch being at such height relative to the lower end of the spring that a certain elevation of the free end of the gate will lift the 60 spring out of engagement with the catch; 7, a similar catch upon holding-post 3, this catch being adapted to be engaged by spring 5 and hold the gate open; 8, a bracket secured to post 1 near the foot of the hinge-stile of the 65 gate, this bracket having ears projecting toward the hinge edge of the gate; 9, a spindle vertically journaled in bracket 8; 10, an arm fast on spindle 9; 11, a hinge-eye in the outer end of arm 10, adapted to receive the pintle 70 of the lower gate-hinge; 12, a stop to limit the turning of arm 10 in one direction; 13, a stop to limit the turning of arm 10 in the other direction, the two stops being so placed as to permit arm 10 to swing through about a quarter of 75 a circle; 14, the upper hinge of the gate; 15, in Fig. 2, a circle illustrating the position of the pintle of the top hinge relative to hinge-eye 11 of the lower hinge when the gate is in closed position; 16, a rectangular block fast on the 80 lower end of spindle 9; 17, ears projecting from two opposite faces of block 16, two ears projecting from one face and two from the opposite face of the block, the two ears of a face being in an upper and lower horizontal 85 plane, respectively; 18, links pivoted to ears 17 and adapted to fold against the appropriate faces of block 16, the arrangement being such, as seen in Fig. 2, that in one angular position of block 16 two of the links lie against 90 the faces of the block, while the other two links are free of the faces of the block and pull directly upon the lugs, uniting them to the block; 19, eyebolts pivoted to the outer ends of links 18 and provided on their outer 95 ends each with a pair of nuts; 20, straps for eyebolts 19, each consisting of a flat plate with an eye in its outer end, its inner end being bent at right angles and having an eye engaging the eyebolt and adjustably secured 100 thereon by means of the nuts; 21, 22, 23, and 24, cables or wires attached to straps 20 and

extending along the side of the roadway, a pair toward and past holding-post 3 and a pair in the opposite direction; 25, a trip-lever of bow form disposed at the side of the roadway in line of wheel trackage at some distance beyond holding-post 3, the bow of the trip presenting itself upwardly and across the wheel-track, so that as a vehicle-wheel strikes it the trip will yield downwardly; 26, an arm fast on the axis of trip 25 and projecting normally upward in the plane of trip 25; 27, a spring connected with arm 26 and serving to maintain the arm and its trip 25 yieldingly in normal upright position; 28, a double-ended arm loose on the axis of trip 25 and disposed against the inner face of arm 26, this double-ended arm having cable 23 connected with its upper end and cable 21 connected with its lower end; 29, a lug projecting inwardly from arm 26 and bearing normally against the forward edge of the lower end of double-ended arm 28 and adapted under certain relative rocking conditions of the arms to engage the forward edge of the upper end of arm 28; 30, a foundation-box sunk in the roadway to furnish a support for the bearings of the trip-lever and for the spring 27; 31, the trip mechanism which has been described, considered as a whole, being that trip which is disposed at the opening side of the gate; 32, a similar trip mechanism, considered as a whole, disposed at the opposite side of the gate and having its double-ended arm connected with cables 22 and 24; 33, an arrow indicating direction of vehicle approach from the opening side of the gate, or, in other words, against the opening direction of the gate, and 34 an arrow indicating direction of vehicle approach in the opening direction of the gate.

40 The drawings indicate the normal position of the parts with the gate closed. If now, looking at Fig. 2, cable 21 be pulled upon, block 16 will be partially rotated, the link 18, pertaining to cable 21, continuing to lie 45 against the face of the block until the block shall have turned through an eighth of a circle, after which the free end of the link leaves the block. During this operation it is necessary, of course, that cables 23 and 24 should 50 have yielded to permit the turning of the block. The turning of the block 16 through about a quarter-turn has the effect of moving hinge-eye 11 farther away from the hinge-post. The obvious result is that the free end 55 of the gate is lifted, and this lift is to be such that spring 25 will come up out of engagement with catch 6, thus leaving the gate in condition to be opened. At the same time the hinge-eye 11 has moved to the right of the 60 vertical plane of top hinge 15, the result being that the plane of the gate is thrown out of the perpendicular, the general hinge-axis becoming inclined, with its bottom approaching post 2 and receding from post 3. Under 65 these conditions of inclined hinge-axis the gravity of the gate causes it to swing open, its free end descending as the swinging takes

place. The gate is finally arrested at holding-post 3, spring 5 snapping behind catch 7. If now, the gate having been thus opened and held, cable 23 be pulled upon, the hinge-eye 11 will be turned back to normal position. This again elevates the outer end of the gate and frees the latch-spring from catch 7 and throws the plane of the gate out of the vertical, whereupon gravity causes the gate to swing to closed position, its free end descending and spring 5 snapping behind catch 6. Thus it will be seen that pulling upon cable 21 or cable 22 the gate will be caused to open and become latched in open position, while by pulling upon cable 23 or cable 24 the gate will become unlatched from the holding-post and caused to close and become latched to the latch-post.

85 Normally both trips stand upright, being so held by their springs. If a vehicle approaches in the direction of arrow 33, one of its wheels, striking trip 25, will depress that trip and immediately pull upon cable 21 and cause the opening of the gate in the manner heretofore described. During this action the proper slack or endwise movement was permitted to cable 23, and when the wheel shall have passed the trip the trip rises to normal position, lug 29 having lost motion with reference to the upper arm of double-ended lever 28, so that arm 28 in its new position will not interfere with the lug. The vehicle, having passed through the open gate, engages at trip 32 and depresses it, the result being that cable 24 is pulled upon, thus causing the gate to close behind the vehicle.

90 It will be observed from Fig. 4 that if a vehicle has actuated trip 25 and that trip has 95 risen behind the vehicle a following vehicle depressing trip 25, or the rear wheels of the same vehicle, for that matter, are of no damaging effect upon any of the trip mechanism, owing to the lost motion between lug 29 and the two arms of lever 28. This applies to both trip mechanisms, and it follows that one trip can never interfere with the action of another or one actuation of either trip bring 100 about conditions of itself or the other trip to 105 be productive of injurious strains in case of subsequent actuation of either trip.

110 I claim as my invention—

115 1. In a gate, the combination, substantially as set forth, of a hinge-post, a latch-post, a holding-post, beveled catches on the latch-post and holding-post, a gate, a spring upon the free end of the gate adapted to snap into and rise out of said catches, an upper gate-hinge uniting the gate to the hinge-post, a 120 bracket on the hinge-post, a vertical spindle journaled in said bracket between the hinge-post and the gate, an arm fast on said spindle, a hinge-eye in said arm engaged by the 125 lower hinge-pintle of the gate and adapted by the turning of the arm to throw the plane of the gate out of the vertical and to lift the outer end of the gate, stops to limit the turning of said spindle, a block fast upon said 130

spindle, four links hinged to the respective corners of said block, two trip-levers, one mounted in the roadway at each face of the gate, a trip-arm on the axis of the trip-lever 5 in the angular plane of the trip-lever, a spring connected with said trip-arm and tending to hold the trip-arm and trip-lever in normal vertical position, a double-ended arm loose on the axis of the trip-lever, a lug upon the trip-arm 10 adapted to engage and turn the double-ended lever and having lost motion with reference thereto, and cables or wires having connection with said links and said double-ended arms.

15 2. In a gate, the combination, substantially as set forth, of a hinge-post, a latch-post, a holding-post, beveled catches on the latch-post and holding-post, a gate, a spring upon the free end of the gate adapted to snap into 20 and rise out of said catches, an upper gate-hinge uniting the gate to the hinge-post, a bracket on the hinge-post, a vertical spindle journaled in said bracket between the hinge-post and the gate, an arm fast on said spindle, a hinge-eye in said arm engaged by the 25 lower hinge-pintle of the gate and adapted

by the turning of the arm to throw the plane of the gate out of the vertical and to lift the outer end of the gate, stops to limit the turning of said spindle, a block fast upon said spindle, four links hinged to the respective corners of said block, two trip-levers, one mounted in the roadway at each face of the gate, a trip-arm on the axis of the trip-lever 30 in the angular plane of the trip-lever, a spring connected with said trip-arm and tending to hold the trip-arm and trip-lever in normal vertical position, a double-ended arm loose on the axis of the trip-lever, a lug upon the trip-arm adapted to engage and turn the 35 double-ended lever and having lost motion with reference thereto, an eyebolt connected with the free end of each of said links and provided with a pair of nuts, a strap engaging each of said eyebolts between the nuts 40 thereof, and cables or wires connecting said straps with said double-ended levers. 45
